UNITED STATES PATENT OFFICE.

FRANK M. SLOUGH, OF FOREST LAWN, NEW YORK, ASSIGNOR TO THE STROMBERG-CARLSON TELEPHONE MANUFACTURING COMPANY, OF ROCHESTER, NEW YORK, A CORPORATION OF NEW YORK.

CALL-DISTRIBUTING TELEPHONE SYSTEM.

Application filed July 1, 1918. Serial No. 242,776.

To all whom it may concern:

Be it known that I, FRANK M. SLOUGH, a citizen of the United States, residing at Forest Lawn, in the county of Monroe and State of New York, have invented a certain new and useful Improvement in Call-Distributing Telephone Systems, of which the following is a full, concise, and exact description.

10 This invention relates to telephone exchange systems, wherein calls from outlying subscribers' lines are automatically extended by electromagnetical means at an exchange, to different operators' positions at the exchange.

While my invention is of wide application, it has a particular application in a system wherein the distribution of incoming calls to the different operators' positions in the exchange switchboard, is accomplished in such a way that the calls will come in to operators' call receiving circuits, or instruction circuits, one after the other in a given order, the calls being allotted to certain call receiving circuits of the operators' positions in rotation.

An object of my invention is to provide in such a system, means whereby if certain operators whose positions are thus equipped with a given number of these call receiving circuits fall behind in the number of calls answered, that they may be assisted by other operators whom I may term "assisting operators" located at "over flow" positions, and calls may be answered by the assisting operators thus enabling the call receiving circuit over which the call is made to be cleared and made ready for another call.

40 Another object is to provide means in such a system, whereby whenever there are a predetermined number of unanswered calls at an operator's position existing on one of these call receiving circuits which are distinct and separate from the operators' link circuits as will be hereafter described, that a signal will be so located at the said helping position that it will indicate to the assisting operator residing thereat, that the first one of the unanswered calls of the first named position is to be attended to by the said assisting operator.

Another object of my invention is to provide a conversational circuit from the call-

ing subscriber's line to the operator's call 55 extending apparatus independent of the call receiving apparatus over which the subscriber has given his order, and to extend the said conversational circuit to a second operator when there exists a certain amount 60 of predetermined number of calls on the first operator's position.

Another object is to release the call receiving apparatus for use at the first operator's position to receive an order pertaining to another call if the first call has been answered by either the first operator or the assisting operator, the said release being effected by either operator after attending to the answering of the first call performing 70 the act of connecting one of the idle link circuits of the operator's position to a different line, the said link circuit being manually selected by the operator.

Another object of my invention is to reduce the amount of apparatus required in the setting up of the connection by the use of a small amount of circuits and apparatus common to a large number of call extending link circuits, and also common to a larger 80 number of incoming call or instruction circuits.

Another object of my invention is to provide in such a system as before outlined, means whereby the operator may manually 85 select any desired idle link circuit located on her position, whereby time is saved in the locating and conditioning such a link circuit to be used.

Other objects of my invention and the invention itself will be more clearly understood from the description of the embodiment illustrated in the drawings which are a part of this specification wherein:

Fig. 1 shows a plurality of telephone lines, 95 two of which are shown herein, as well as a central office apparatus operating in connection therewith, the substation apparatus of one of the lines being shown in Fig. 1, and the substation apparatus of the other 100 line being shown in an extension of Fig. 1, on the sheet of drawing containing Fig. 5. Fig. 1, also shows a system of interconnecting intersecting trunks provided for the purpose of extending a call originating on one of the telephone lines to one of a plurality of interconnecting trunk circuits which are extended, as shown in Fig. 3. Fig. 1, also

shows a plurality of code wires from impulse apparatus shown in Fig. 2, and means for extending connections from these code wires to code conductors of the interconnecting trunk circuits, the particular code wires thus extended depending upon the numerical position which the line occupies on the connector switches shown in Fig. 5, their calling line extending a different combination of code wires.

Fig. 2, illustrates a system of code interrupter wheels, whereby current impulses are caused to be made, there being an interrupter for each numeral from 1 to 10, and there being four groups of the said interrupters to denote thousands, hundreds, tens and units digits which may be combined to designate the calling line numbers. Code wires extend from these interrupter wheels to the line relays illustrated in Fig. 1, one code wire from each set of interrupters being associated with each telephone line. A master impulse wire is also extended from an interrupter shown in Fig. 2 to apparatus of Figs. 4^A and 4^B as a starter wire to mark the beginning of a train of impulses and the end thereof, that a given train of impulses which characterize a given calling line may operate switches of a selective system illustrated in Fig. 5, to select the calling line, the train of impulses being composed of consecutive series of interruptions from the different order of code wires.

Fig. 3, illustrates a system of interconnecting intersecting trunks similar to that shown in Fig. 1, one of the sets of trunks being that before referred to as being extended from Fig. 1, and the other set of trunks being so arranged that the trunks of one set may be connected to a trunk of another set under the control of controlling apparatus shown in Fig. 3; the trunk of the second set being extended to Fig. 4, where it is shown terminated in a call receiving or operator's instruction circuit.

Fig. 4, shows the extension of the call receiving circuits from the trunking system of Fig. 3 and shows operator's apparatus, whereby an attendant operator may connect her telephone set to the call receiving or instruction circuits of her position to receive a call and thus ascertain the number of the called line desired by the calling line party. Fig. 4 also illustrates a plurality of instruction circuit-link circuit assisting junction circuits, whereby a previously attended instruction circuit and a subsequently manipulated link circuit may be by the act of an operator in manipulating the link circuit, joined together for a given interval wherein selective switches perform the function of interconnecting the said link circuit, and the calling line terminals, the said connection being performed independent of the said instruction circuit or the said junction circuit,

Associated with the said junction circuits are shown extensions of a plurality of link circuits, which link circuits are extended to the disclosure of Fig. 4^A. Fig. 4, shows in addition to two instruction circuits completely illustrated, three others incompletely illustrated and a system of circuit conductors, relays, etc., whereby upon as illustrated in Fig. 4, whenever three instruction circuits having calls residing therein, the first of the said link circuits will be operated to extend a signal to a different operator's position called a "helping" position and the signals of the link circuit residing in the first position will be altered in character to designate the transference of the call, whereby the helping operator will be apprised of her duty to answer the call, and the first or home operator will be apprised of the transference.

Fig. 4^A, shows the main portion of the link circuits having extensions in Fig. 4 as before mentioned, one of the said link circuits being in Fig. 4 completely illustrated, the other being incompletely illustrated; there being contained in Fig. 4^A also operator's set apparatus and ringing generator apparatus for the home operator's position.

The helping operator's position apparatus is shown in Fig. 4^B, extensions of the instruction circuits of Fig. 4 being illustrated therein for the use of the helping operator, interconnecting junctions are also provided to interconnect the instruction circuits for a brief interval after the operator has performed the act incidental to the making of connection with the called line; this is the embodiment illustrated consisting of placing the plug of the chosen link circuit into the multiple jack of the called-for line. This use of junction circuit, instruction circuit and link circuit to make a connection is like that illustrated for the home position, the apparatus for which is shown and will be described in connection with Fig. 4.

Fig. 4^B also shows the operator's set and operator's common ringing apparatus.

Fig. 5, shows diagrammatically a system of selective switches for extending the terminals of link circuits as illustrated in the foregoing figures to the terminals of a calling line, such as the line having the substation A shown in Fig. 5.

When the apparatus is taken for use by the manual selective act of an operator, the apparatus is so arranged that current impulses will be transmitted over a private circuit conductor leading from the right of Figs. 4^A or 4^B as the case may be, to operate selective switches indicated in Fig. 5 of an automatic selective system which may be any of the common types known to the art and which in the embodiment illustrated in this description is shown as being such a system as is illustrated and described in the patent

to A. E. Lundell, No. 1,194,851—whereby the apparatus of Fig. 4 under the control of the current impulses, controls the operation of the apparatus of Fig. 5 to connect to 5 the link circuit conductors which are extended from Fig. 4 through the apparatus of Fig. 5, the talking conductors of the calling line. The current impulse apparatus of Fig. 4 is operated under the control of the 10 code apparatus of Fig. 2, circuit conductors from which are extended by means of the apparatus of Figs. 1, 2 and 3 to that of Fig. 4.

Referring now to the figures, Fig. 2 shows 15 code impulse apparatus herein illustrated as composed of a series of interrupter wheels making interrupted contact with operated contact springs. These interrupter wheels are preferably mounted on a constantly rotating shaft not shown and are arranged in 20 four groups of ten each which I term units, tens, hundreds and thousands groups. Preferably the interrupting segments of the wheels are so arranged that none of those 25 of the second or tens set will be operated during the operative period of those of the first set, and the same is true of the third and fourth sets; that is, each set will produce its contact interruptions one after the other, 30 the thousands operating first, the hundreds second and tens third and the units last in order, there being a time interval between the operation of each successive group.

Code wires extend between the contact 35 springs operated by a different interrupter wheel to apparatus associated with the subscribers' lines shown in Figs. 1 and 5, and the current impulses produced by the interrupter wheels are relayed through apparatus of 40 the subscribers' lines brought into action by the act of a subscriber making a call, to a conductor of a call receiving circuit, such as illustrated in Fig. 4, the combination of code wires for each of the lines being different 45 from the combination of any other of the lines. This arrangement provides means whereby automatic apparatus brought into action by an operator in connecting one of the operator's circuits of Fig. 4^A or Fig. 4^B to 50 the called line, will set in operation automatic switches to extend this operator's circuit to the calling line. The automatic switches set in motion are directly controlled by impulses from the interrupter wheels of Fig. 55 2. As soon as the automatic switches have connected the calling line to the operator's circuit which has been extended to the called line through the agency of a plug and jack, the circuits which set in operation the automatic switches and which serve merely for 60 the purpose of an instruction circuit for informing the operator of the designation of the wanted line, revert to common use.

In the embodiment illustrated, I show apparatus to select the particular call receiv-

ing circuit to be used for a given incoming call, the selecting apparatus illustrated in Fig. 3 providing for the consecutive selection of call receiving circuits. These call receiving circuits may be distributed among 70 a plurality of operators and a sufficient number are provided, so that when the apparatus has selected all, many of the first selected call receiving circuits will have been discharged from use by the connective act of 75 operators and again be conditioned to receive new calls. In this way I obviate the necessity of complicated interconnecting apparatus for these call receiving circuits to 80 select busy or non-busy call receiving circuits, and I also by this means provide a very even distribution of the calls throughout the entire switchboard.

In order to reduce the number of such 85 call receiving circuits necessary, I provide means under the control of an operator to limit the time of use of each call receiving circuit, that is, the call receiving circuit is not required to be used for the period of 90 conversation between connected subscribers' stations, but only until such a time as the 95 subscribers are connected together in conversational circuit, the call receiving circuit then reverting to its idle condition, being dissociated from the connection circuit from which it is thereafter independent during the period of the conversational connection previously set up.

I also provide for each operator's position 100 a plurality of interconnecting circuits, whereby an operator may manually select one of the said interconnecting circuits. The selected interconnecting circuit will thereupon under the control of the identifying means above referred to, thru the intervening 105 call circuit cause selective switches of an automatic selective switching system to operate to connect the calling line directly through the said switches to the interconnecting circuit. The call receiving circuit is thereupon discharged from the connection and the subsequent operation of the interconnecting circuit is very much like that of a cord circuit in the ordinary manual telephone system, the called-for subscriber being signaled and the supervising of the connection being taken care of by signal lamps within the view of the operator, and the operator having access to the connection by listening keys and capable of severing the connection 110 by disabling the connection switch of the interconnecting circuit.

Whenever a predetermined number of unanswered calls reside in instruction circuits 115 in a given home operator's position such as is illustrated in Fig. 4, and in the embodiment illustrated in Fig. 4 when as many as three instruction circuits have calls residing therein, I have provided automatic operating means to extinguish the calling signal 120 130

of such an instruction circuit and to operate the call signal of the instruction circuit located at the helping operator's position, the said signal and helping operator's apparatus being shown in Fig. 4^B. Also by the above automatic operation, a transfer signal is operated at the home operator's position, the said signal being individual to the first of the three instruction circuits above stated 10 to have calls residing therein, so that instead of as has been common practice, the last incoming call to the operator's position being transferred when more than a predetermined number of calls reside on the operator's position, I so arrange the apparatus so that the first incoming call of a predetermined number is transferred, thus giving the subscriber who has been awaiting attention the longest a chance of being answered by a new operator upon whose position there may not be many unanswered calls.

I contemplate, though I do not specifically illustrate, means at this helping position 25 consisting of switching keys whereby any one of a number of helping operators working in a group adjacent to the helping position, may by suitably operating a switching key answer the call, so that the use of such a helping position or switchboard section 30 may inure to the benefit of the subscriber, in that, very rapid answering may be obtained on this helping position, if desired. Such a switching key in its simplest form 35 would be a manually operated three-way switch having four blades and alternate contacts for each blade co-operating therewith.

Having thus described my invention in its broadest aspects, I will now describe the 40 specific embodiment there illustrated in the drawings accompanying this specification, and will also describe the operation of the system from which other objects of my invention than those above referred to will 45 be present.

Referring now to Fig. 1, at L and LL, I show central office apparatus individual to two telephone lines extending from substations shown at AA for the line LL, and at 50 A in Fig. 5 for the line L. Circuit conductors *a*, *b*, *c*, *d*, extend from the line circuit L to like referenced conductors of Fig. 5 in which figure multiple jacks J1 and J2 are provided for the line L, and connector 55 switch contacts *cc*, *dd* and *bb* are likewise provided for the line and shown in Fig. 5, the conductors *c* and *d* being the line talking conductors that lead from the apparatus of Fig. 1 to the substation apparatus at A on Fig. 5.

Assume now that the subscriber on the line L whose substation apparatus is shown at A, desires to make a call, he will do so by removing the telephone receiver *r* from 65 the hook closing the switch hook contacts *s*,

and closing a circuit thereat to bridge the line conductors *c* and *d* which lead from that portion of the line circuit shown in Fig. 5 to the line apparatus of the line L shown in Fig. 1, and thru normal contacts 1 and 3 of the line cut-off relay C and the battery feed tandem windings 4 and 5 of the relay 6 to the positive and negative poles of the central office source of current, from which source current will flow thru the said windings over the said line to supply energizing current for the transmitter of the substation A, and to operate the relay 6. The relay 6 will thereupon attract its armatures closing contacts 7, 8 and 9 in circuits to 70 be described. The contacts 8 and 9 being closed, two co-operating circuits will be thereby completed thru the windings 10 and 11 of the relay 12 which may be called the line impulse relay, which circuit includes 75 the four circuit conductors *u*, *t*, *h* and *th*. These symbols relate to the units, tens, hundreds and thousands digits of the number characterizing the subscriber's line L with which the thereby referenced circuit 80 conductors are associated. Similar circuit conductors to *u*, *t*, *h* and *th* for the line L are provided for all of the lines of the system being described, the conductors *iu*, *tt*, *hh* and *th-th* designating like conductors for 85 the line LL.

This description will be confined to the operation of the system wherein the line L is the calling line, and the line LL is the called line of a circuit connection to be 90 established, and the establishment of which connection is described.

At the lower part of the sheet of Fig. 1 are shown four groups of circuit conductors, there being ten circuit conductors in each 105 group. These circuit conductors I term code wires, the first group of code wires being for the purpose of providing the units designation of any telephone line, the second group being provided to designate the tens digit 110 of a telephone line, the third group the hundreds digit and the fourth group the thousands digit thereof. These code wires are shown extended from Fig. 1 to Fig. 2, and on Fig. 2 are shown the code interrupting wheels for each of the circuit conductors of the four groups. Other circuit interrupting mechanism than that specifically shown in Fig. 2 may be associated to perform the functions required of the specific 115 structure shown in Fig. 2. In the embodiment illustrated the code impulse wheels are assumed to rotate synchronously as on a common rotating shaft together with a master impulse wheel *w* shown to the left of the 120 four groups of impulse wheels in Fig. 2. The right-hand row of impulse wheels shown in Fig. 2 are connected in electrical circuit with the ten code wires of the group TH, each conductor of the ten 125 130

in the group being connected to a different impulse wheel; the bottom conductor of the group shown in Fig. 2 leading to an impulse wheel TH-1, and the top code 5 wire of the thousands group leading to the impulse wheel TH-10, the first named impulse wheel having a single short circuit interrupting insulating piece in the periphery of the conducting segment thereof, and 10 the last named impulse wheel having ten short circuit interrupting insulating pieces in the periphery of its circuit conducting segment; the other intermediate code wires being connected to impulse wheels having 15 different numbers of insulating circuit interrupting pieces, from two to nine pieces in the various wheels, these insulating pieces being so arranged as shown in the drawing in what may be called the first quadrant 20 of the wheel circumferences. These conducting segments of the thousands interrupter wheels of the first group are connected to the negative pole of battery. The hundreds 25 interrupter wheels are similarly provided with insulated pieces to provide conducting segments which are in the second quadrant of these wheels with respect to the conducting segments of the thousands wheels.

It will be noted that between the first and 30 second quadrants in each group of wheels above mentioned, there is a circuit conducting space on the periphery of the wheels considerably broader than the circuit conducting spaces between the insulating pieces. 35 The two other groups of the wheels for the tens and units designations are like the wheels of the thousands and hundreds designations just described, only the circuit conducting portions and the insulating pieces 40 are arranged just 180 degrees away from the like portions of the before described wheels. In this way four wheels for like digits in the different groups will produce a like number of circuit interruptions, only 45 the circuit interruptions will not occur simultaneously, being produced in regular order one after the other as the four circuit interrupting quadrants come successively under the brushes attached to the code wires 50 which are all arranged in the embodiment illustrated, to contact on the same side of the wheels. The circuit conducting segment of the thousands as has been described, is connected to the negative pole of battery, 55 the hundred group to the positive pole of battery, the tens group to the negative pole of battery, and the units group to the positive pole of battery.

The impulse relay 12 of Fig. 1, has its 60 windings 10 and 11 placed in series with the units and thousands, the tens and hundreds code wires, respectively, by the operation of the relay 6 closing contacts 8 and 9 as before described, and each wheel of the two 65 pairs produces current impulses of differ-

ent polarity. It is apparent that current impulses will be produced in the circuits described, thru the said windings 10 and 11, producing sets of magnetic impulses one after the other in the core of the said relay, 70 so that the contacts 13 thereof will be vibrated to produce successive trains of current impulses characterizing the four digits comprising the number of the calling telephone line. The short contact piece of the wheel 75 W which is connected to the ground pole of battery as will be later more fully described produces a single impulse of current over its connected conducting wire after the associated circuits as will be later described, 80 are properly conditioned, the timing of this single current impulse being such that it will occur just before the thousands train of circuit interruptions begin. The circuit conductor leading from this master impulse 85 wheel leads to the interconnecting circuit mechanism of Fig. 4 which will be later described.

When the relay 6 was operated, contacts 7 were also closed completing a circuit from 90 the negative pole of battery, thru the resistances 14 and 15 to the ground pole of battery, and thereby raising the electrical potential of the circuit conductor 16 leading thru the winding 17 of the line cut-off 95 relay C of the line and the circuit conductor a leading to like referenced circuit conductor a of Fig. 5 to the thimbles of the multiple jacks J1 and J2 of the calling line. This raises the electrical potential of the 100 said multiple jack thimbles and conditions the line to test busy when the ordinary manual busy test is made by touching the plug of an interconnecting circuit to the said thimbles in the usual manner. A 105 branch circuit is also closed by the contacts 7, the circuit being traced thru the said contacts and a winding 18 of a connection relay 19, and thru normal contacts 20 of a relay 21 to the ground pole of battery. 110

The object of the completion of the circuit just traced, is to interconnect circuit conductors c, d and f of the calling line to an intersecting trunk circuit, such as the trunk circuit B or the trunk circuit D, the trunk B in the description being taken as the seized trunk circuit, but if the trunk circuit B is busy, that is, taken for use by another line such as the line LL, the relay 21 would have been operated, and the contacts 20 115 opened so that the circuit just traced including a winding 18 of the relay 19 would not have been completed, but instead a circuit would have been completed comprising a winding 18 D of a relay 19 D, the circuit being established through contacts 20 D of a relay 21 D, all associated with the trunk D, and having parts which correspond to parts referred to for the trunk B. Likewise if the trunks B and D were busy, the next suc- 120 125 130

ceeding trunk would be seized for use upon the initiation of the call by the subscriber at A as described. The circuit just traced being completed, current will flow over the 5 same from the source of current included in the circuit thru the winding 18 of the relay 19, and then will cause this relay to be energized thereby attracting its armatures and closing contacts 22, 23, 24 and 25. 10 The contacts 22 being closed, a holding circuit is thereby established for the relay 19, including its winding 26, the circuit being traced as follows: from the negative pole of the source of current, the now closed contacts 15 7 of the relay 6, the winding 26 of the relay 19, the now closed contacts 22 thereof, the winding of the relay 21 which is individual to the trunk circuit and common to the group of lines capable of being connected 20 to the trunk; the circuit being thereafter traced thru conductor R which leads to a like referenced conductor R on Fig. 3, where the circuit of the trunk line may be seen extended, and thru the winding of 25 the relay 27 to the ground pole of the source of current. This will cause the operation of the relay 21 to open contacts 20, whereby another line may not be connected to the trunk line B, and will cause the contacts 28 30 to be closed extending the circuit of the connecting ground or the trunk seizing circuit to contacts of a like relay for the trunk circuit D which is assumed to be the next succeeding trunk circuit capable of being seized 35 for use by a calling line. The relay 27 will also be operated in series with the relay 21, and will attract its armatures closing contacts 29 and 30. The contacts 29 being closed, a circuit will be completed including 40 the said contacts traced as follows: from the negative pole of the source of current thru the said contacts 29 and winding 31 of the relay 32, contacts 33 of a relay 34, a brush 35, a contacting segment 36 of a rotary switch SW, and thence thru the winding of a relay 37 to the ground pole of battery. This circuit being closed, current 45 will flow over the same operating the relay 37, which being of very high resistance will so limit the strength of current flow, that the serially included winding 31 of the relay 32 which is of relatively low resistance will not energize the relay 32 sufficiently to operate its contacts. The relay 32 and a like 50 relay 132 for the trunk line D, are arranged to interconnect a call receiving circuit M to the associated trunk line B or D.

In this description, although but two trunk lines of each type are shown, it is understood that other trunk lines might be employed in practice to increase the volume of service as may be required of the trunks.

The relay 34 is individual to the call receiving trunk line circuit M and is common

to all of the trunk lines B and D which may have access to the trunk M. The switch SW and the associated magnets 37 and 38 together with associated apparatus is common to all of the call receiving trunk lines, such as M and N shown in the drawing of Fig. 3, and operated to condition a next succeeding call receiving circuit for a subsequent call upon the establishment of a preceding call connection whereby an incoming 75 trunk line, such as B or D is connected to a call circuit.

It is understood that other forms of interconnecting switch mechanism may be employed to produce the interconnection of the 80 trunk lines of the various types, such as rotary switches or cross-bar switches, as are a part of the art.

The relay 37 having been operated, the contacts 39 thereof will be closed completing 85 a circuit including the source of current, and the completing of the slow releasing magnet 38 which is the motor magnet for the switch SW, the switch SW being of the back stroke type, being propelled from one operative 90 position to another upon the deenergization of the slow releasing magnet 38, which may be made slow releasing in any suitable way. The magnet 38 being operated, the armature thereof will be attracted and will cause the 95 carried pawl to fall into the next succeeding notch of the ratchet wheel RW, so that upon the deenergization of the magnet 38 which now takes place, the ratchet wheel RW will be propelled by the action of the spring 40 100 to its next position of rest causing the next operative position of the switch SW. The magnet 38 being energized, contacts 41 will be closed upon a full attraction of the armature short circuiting the high resistance relay 37. This will produce a slow releasing 105 of the armature of the relay 37 and of the slow release relay 38, but in the meantime will accomplish the operation of the relay 32 by increasing the flow of current from its 110 winding 31 in the circuit which has been described.

The relay 32 having been operated, a locking circuit will be completed therefore, including contacts 42 and a winding 43 thereof, and windings of the relays 34 and 44 of the call receiving circuit, the relay 44 being shown in Fig. 4. This locking circuit is traced as follows: From the negative pole of the source of current thru the contacts 115 30 of the relay 37, the contacts 42 and the winding 43 of the relay 32, the winding of the relay 34, circuit conductor R, which is shown in Fig. 4, and the winding of the relay 44 to the ground pole of the source of 120 current. Current from the said source will flow over the said circuit, causing the relay 32 to remain operated and causing the operation of the controlling relay 34 and the relay 44 of the call receiving circuit. The re- 125 130

lay 34 being operated, contacts 33 thereof will be opened to open the circuit leading to the relay 37, and also to open the common circuit of the trunk seizing windings as 31 5 and as 131 of such another trunk connecting relay as 32 and 132, so that the call circuit cannot be taken for use by another incoming call of another trunk. The relay 44 being operated will close its contacts 45 and 46, the 10 contacts 46 completing a circuit for the answering signal lamp 47, thru normal contacts 48 of a relay 49, this circuit including the source of current, and the lamp 47 will be operated to apprise the operator that a 15 call exists on the call receiving circuit M, with which the lamp 47 is associated.

Another call receiving circuit is shown at X in Fig. 4 for the same operator's position. Other call receiving circuits, such as N shown 20 in Fig. 3, lead to call answering apparatus on other operators' positions. The call circuits M, N and others not fully shown in Fig. 3, but which it is understood may be included in the system of my invention lead to 25 other operators' positions, the preferred order in which these call receiving circuits are allotted for the use of succeeding incoming calls by the call allotting switch SW, being such that the first call receiving circuit 30 of the first operator will first receive a call, then the first call receiving circuit of the second operator, and then so on until all of the operators have had a call associated by the call allotting switch SW in the first 35 call circuit of each operator's position. Thereafter the said call allotting switch will allot calls to the second call receiving circuit in order to each position until calls have been allotted to all call receiving circuits, which 40 preferably may be five in number for certain conditions in telephone traffic which are obtainable in practice, whereupon the call allotting switch SW will again allot a call to the first call circuit of the first operator and 45 so on, it being proposed to thus distribute the calls in absolute rotation as to call circuits and as to "home" operators' positions.

The line talking conductors *c* and *d* of the calling line have now been extended by 50 means of contacts 23 and 24 of the relay 19 of Fig. 1, and by contacts 50 and 51 of the relay 32 of Fig. 3, to the listening key springs 52 and 53 of the listening key 54 of Fig. 4. The so-called "home" operator may now answer the call on the call receiving circuit M, by operating the listening key 54, and closing the contacts thereof to connect her operator's telephone set shown at O in Fig. 4^A, to the talking conductors of the telephone line 55 extended as described. The operator conversing with the subscriber will learn the number of the called-for line. In the operation of the listening key, contacts 55 were closed completing a circuit for the relay 49, the said circuit including the source of cur-

rent, the winding of the said relay, and contacts 55 and contacts 45 of the operated relay 44. This will cause the relay 49 to be operated, which immediately closes the locking circuit for itself including its winding and 70 its contacts 56, independent of the contacts 55 of the listening key. The listening key may now be opened, the relay 49 remaining operated through its locking contacts. The signal lamp 47 is extinguished and a signal 75 lamp 57 will be lighted in its place to indicate that the call on the call receiving circuit M has been answered, but the desired connection not yet completed.

The circuit for the lamp 57 includes now 80 closed contacts 58 of the relay 49 and normal contacts 59 of the relay 60, and contacts 46 of the relay 44, together with circuit conductors leading through the said contacts, and including the source of current. 85 The operator having learned the number of the called-for line, will now complete the connection by means of one of a plurality of connection switches under her control and which are herein illustrated as being plug 90 and jack manually operated switches. The operator may use any connecting plug of the group provided for the purpose, and time is thereby saved in completing connection, 95 since an operator upon completing one connection by manipulating one connection plug, may immediately manually preselect the plug for the next connection by picking up such a plug as she desires to use for the next connection. 100

In the illustrated form of my invention I arrange multiple jacks of the called lines on the operator's position in proximity to the said plug, whereby the operator may by inserting the plug into the said multiple jacks, 105 make connection with called lines. Such an act will cause an association of the call receiving circuit last attended and the particular plug circuit manually selected. This is not a permanent association as will be seen 110 from the further description.

To continue the narrative, the operator having manually selected an idle plug circuit, will make the busy test in the usual way by touching the tip of the connecting 115 plug, such as the connecting plug P1, shown in Fig. 4^A, to the thimble of the called line jack which we will assume is the jack J3 for the called line LL, shown in Fig. 1. If the called line is busy, the busy condition of the 120 line will be indicated to the operator by the existence of a raised potential of the jack thimble of the jack J3 with reference to the potential of the ground pole of the exchange source of current. This is accomplished by the 125 means shown and described for the line L consisting of the contacts 7 of the relay 6, the resistance coil 14, and the winding 17 of the relay C which provided a circuit from the negative source of current to the 130

thimbles of the line jacks J1 and J2; or it may be done by a connecting plug being previously placed in one of the multiple jacks of the line, such as the jack J⁴, whereby the shank of the plug to which is connected a circuit leading to the negative pole of battery makes contact with the said thimble to raise the potential thereof. If the line is busy, current from the said negative pole of the source of current will when the busy test is made, traverse the tip of the talking strand 461 of the connecting circuit CP thru normal contacts 462 of the relay 463, and normal contacts 464 of the relay 465 to the common test relay 466 for the operator's position, and thru the said relay to the ground pole of the source of current, energizing the said relay, causing it to close its contacts 467 and thereby establishing a circuit for the flow of current from the source of current including an inductive winding 468 on the operator's induction coil inductively related to the operator's receiver 469, which will thereby be operated giving the characteristic busy click. The operator will thereupon tell the subscriber that the line desired is busy. The subscriber by restoring his receiver to the hook will open the contacts of the hookswitch, releasing line relay 6 which by its contacts 6 operated the relays which have been described as having been operated on the establishing of this connection to the present point of description, and these relays will therefore be released, restoring the apparatus to normal. The operator if she does not find the line busy, will insert the plug P1 for the connecting circuit CP into the jack J3 of the called line, making connection thereby with a pair of talking conductors of the line and a local private wire of the line circuit to like talking conductors and a private wire of the connecting circuit CP. A circuit will thereupon be closed including a winding of the cutoff relay 71 of the called line and the winding of the relay 465 of the connecting circuit, the said circuit including the source of current; current from the said source will flow over the said circuit energizing these relays which will attract their armatures.

The contacts 72 and 73 of the relay 71 of the line circuit will be opened to remove the normal association between the call initiating apparatus of the line circuit and the line circuit proper. The contacts 74 of the relay 71 will be closed placing the winding 75 of the relay 71 in multiple with the winding 70. The relay 465 of the connecting circuit CP shown in Fig. 4^A being operated, will close its contacts 476, 477, 478 and 479 and open its contacts 464. The opening of the contacts 464 will dissociate the busy test relay 466 from the connecting circuit. The closing of the contacts 476 will complete the

connection of the winding 480 of the tip supervisory relay to the talking strand 461 of the connecting circuit. The closing of the contact 477 will complete a circuit including the source of current and normal contacts 482 of the relay 483 for the supervisory lamp 484, lighting the said supervisory lamp, this association being accomplished by circuits temporarily established over intermediate switching circuits of which there would be provided only a few for each operator's position. The function of these intermediate junction circuits is to extend the circuit of the impulse conductor, such as the conductor 106 of the incoming call circuit M shown in Fig. 4, through the apparatus of the connecting circuit, such as CP, to convey the controlling impulse through the said connecting circuit and to switching apparatus which may be associated therewith. The said switching apparatus will then establish a talking circuit from the said connecting circuit, which at this time has established a talking connection with the called-for line terminals to the talking terminals of the calling line. In the system of my invention I find that since the time of use of what might be called the impulse sending apparatus is relatively short compared with the total time of connection to limit the number of such impulse conductor extending links or junctions, to a very small number such as 2 junctions common to a much larger number of connecting circuits as CP, and common to a larger number of incoming call circuits, such as M and X. Such interconnecting links and associated apparatus is shown at T and U, having in the embodiment illustrated, terminal connecting relays 88 and 988 for the junction circuits T and U respectively, wherewith to connect either of these junction circuits T or U to the incoming call circuits M, and these junction circuits T and U likewise have like relays wherewith to connect them to other incoming call circuits such as the line relays shown for connecting to the incoming call circuit. The junction circuits T and U likewise have terminal connecting relays 511 and 512 to connect the junction T or U respectively, to the connecting circuit CP² in Fig. 4^A, and the junctions have also terminal connecting relays 513 and 514 to connect the junction T or U respectively, to the connecting circuit CP of Fig. 4^A. Common controlling relays 515 and 516 for the junction circuit T, and 517 and 518 for the junction circuit U, are provided to perform functions during the interconnection process, which will be apparent from the description of the operation of these relays which follows.

The relay 465 of the connecting circuit CP of Fig. 4^A having been operated as de-

scribed by the act of the operator making connection with the called line terminals, its contacts 479 will be closed completing a circuit from the negative pole of battery, 5 through the said contacts, through the normal contacts 485 of the connecting circuit 486, over the conductor 519 which is extended in Fig. 4, and through the winding 520 of the relay 514, through the winding 521 of the relay 517, and through normal contacts 522 of the controlling relay 518 to the ground pole of battery. Current from the negative pole of the source of current would not flow over the circuit just traced from 10 Fig. 4^A through the winding 523 of the relay 513, for the reason that the ground pole of battery would not be connected to the contacts 524 of the relay 516 as they are to the contacts 522 of the relay 518, since in 15 order to accomplish this, the relay 518 would have to be operated closing the contacts 525 of the relay 518 to extend the ground pole of battery to the contacts 524 before mentioned. Therefore, at this time the conditions are such due to the relay 518 being 20 inoperative, that the junction circuit U rather than the junction circuit T is selected for the linking of incoming call and operator's connecting circuits involved in the 25 setting up of the present described connection.

The circuit above described being completed, current will flow over the said circuit operating the relay 514 and the relay 30 517, due to current traversing the windings 520 and 521 respectively, of these two relays. These relays being operated they 35 will attract their armatures, the relay 521 thereby closing its contacts 526 to cause a further extension of the interlinking operation. In furtherance of this extension a 40 circuit will be completed from the ground pole of battery, through the contacts 526, windings 533 of the relay 517, and over the circuit conductor 527 leading to windings, 45 such as 528 of the relay 529 for the incoming call circuit X, to the winding 530 of the relay 988 for the incoming call circuit M. A circuit is only completed, however, 50 through one of the said windings, namely, the winding 530 of the relay 988, since only the incoming call circuit M is in that state of operation produced by the previous answering of an incoming call residing therein, 55 and in consequence to such answering the relay 49 of this incoming call circuit M has been operated and operatively locked to close contacts 531 thereof in the circuit of the winding 530 of the relay 988 to complete the circuit including this winding 60 which is being traced, this circuit also including normal contacts 532 of relay 60 of the incoming call circuit M. This circuit being completed, the relay 988 will be operated, and the relay 517 will for the mo-

ment be retained in operation by current flowing over this circuit. The relays 988 and 514 being operated, a circuit will be completed through contacts 534 and 535 of these relays respectively, the said circuit 70 leading from the ground pole of the source of current, through the normal contacts 536 of the relay 537, the contacts 46 of the relay 44, the winding of the relay 60, the contacts 534, the winding 537 of the relay 75 988, the winding of the relay 518 of the junction circuit U, the winding 538 and the contacts 535 of the relay 514, circuit conductor 539 which is extended on Fig. 4^A and in Fig. 4^A leads through the winding of the 80 relay 486 to the negative pole of the source of current. Current from the said source will flow over the said relay windings serially included, retaining those relays in operation which have been described as previously operated, and operating the relays 486 of the connecting circuit CP, the controlling relay 517 for the junction circuit U, and the relay 60 of the incoming call circuit M. The relay 518 being operated 90 will open its contacts 522, thus disabling the relay 512 that another connecting circuit may not be connected to the same junction circuit U. The contacts 525 being closed, extend the circuit from the ground 95 pole of battery to the contacts 524 of the relay 516, through which the ground is extended to the windings of the relays 511 and 513 to condition these relays for operation so that if, while the junction circuit 100 U is in use that upon the next succeeding connection being established, the junction circuit T may be taken for use in the establishment of the said next succeeding connection.

The relay 518 being operated, its contacts 541 will be closed short circuiting the winding 533 of the relay 517, and the winding 521 of the relay 517 having its circuit opened at the contacts 522 of the relay 518, the 110 relay 517 will be disabled and will return its armatures to its normal unoperated position, the return being accomplished however slowly, due to the retarding effect of the short circuited winding 533, this so that 115 the holding circuit in which is included windings of relays 988, 514 and 486 may be completely established prior to any possible disabling of the establishing energizing circuits for these relays. Such establishing circuits are now broken at the contacts 532 of the relay 60, at the contacts 522 of the relay 518, and at the contacts 485 of the relay 486; the latter being in the connecting circuit CP.

The contacts 59 of the relay 60 are now broken extinguishing the signal lamp 57 to indicate the association, which association is perhaps more directly produced by the lighting of the signal lamp 96, which is in 130

cluded in a circuit with the source of current and now closed contacts of the relay 60. This lamp 96 will remain lighted during the full period in which the talking conductors of the connecting circuit are extended by the operation of automatic selective apparatus to make connection with the talking conductors of the calling line, as will be described.

10 The contacts 498 of the relay 486 are now closed completing a circuit from the common master impulse wheel shown in Fig. 2 and indicated as *w*, the circuit being only completed at such intervals as occur when 15 the short segment 99 makes contact with the brush 100 to mark the intervals between successive trains of code impulses denoting calling line number designations. As soon as the contacts 99—100 of the rotating impulse wheel make contact, a circuit is completed from the ground pole of battery, through the said segment and brush of the impulse wheel, circuit conductor *ww* leading from Fig. 2 and extended in Fig. 4^A, 20 the said circuit being completed through contacts 498 of the relay 486, normal contacts 501 of the relay 502, the winding of the relay 503 to the negative pole of the source of current through contacts 478 of 30 the relay 465. Current flowing over this circuit will operate the relay 503. This relay being operated, will close its contacts 504.

When the line conductors *c* and *d* of the calling line were extended by means of contacts 23 and 24 of relay 19 of Fig. 1, and by contacts 50 and 51 of the relay 32 of Fig. 3 to the listening key springs 52 and 53 of the listening key 54 of Fig. 4, as has been previously described, a circuit was also completed to extend in like manner the circuit conductor *f* which I call the impulse wire, from the intermittently operated contacts 13 of the relay 12 of the calling line circuit through contacts 25 of the relay 19, through 45 contacts 105 of the relay 32 to the conductor 106 of Fig. 4, and which conductor 106 is later further extended by the closing of contacts 93 of the relay 988 and by the closing of the contacts of the relay 517 upon the insertion of the plug P1 into the jack of the calling line; the extension being made thereby to the conductor 107 leading through normally closed contacts 508 of the relay 509 shown in Fig. 4^A, and now through the 50 contacts 504 of the relay 503, the said contacts having been closed as described by the operation of the relay 503, and over circuit conductor 110 of Fig. 5, and through the winding of the stepping relay 205, to the negative pole of the source of current shown in Fig. 5.

Fig. 5 shows automatic electrically operated switches, together with circuit conductors and controlling apparatus for the 65 said switches, whereby line talking conduction

tors, such as the talking conductors 111A and 112A of the connecting circuit CP, are extended through contacts of the said switches to the terminals *cc* and *dd* of a telephone line having line conductors *c* and *d*, 70 and as shown in the drawing of Fig. 5 having a substation A connected to the said line conductors.

The switches and circuits employed on the present invention may be of any desired 75 structure to perform the functions desired as above explained, but for the purpose of illustrating my invention, I have illustrated with slight modifications the structure disclosed in the patent to Alben E. Lundell, No. 80 1,194,851.

In the drawing of Fig. 5 showing this system, 111A and 112A represent the extended talking conductors of the connected circuit CP shown in Fig. 4^A; 203 and 204 represent 85 normally opened contacts in the automatically selected connecting circuit which are closed immediately following the association of the said connecting circuit with the plug connecting circuit of Fig. 4^A. 205 is 90 an impulse relay which responds to impulses repeated over conductor 110 to successively operate the stepping magnets of the several switches. Batteries of different potential are indicated in the drawing of Fig. 5. 95 Certain of these batteries which are indicated as being merely of two cells, may be of 24 volts potential, the other batteries indicated as being of 4 cells, may be of 48 volts potential. A selective system producing equivalent results to that shown in Fig. 5 and having a source of current of but one potential may be employed instead of that illustrated.

The series of interruptions produced by 105 the contacts 13 of the relay 12 shown in Fig. 1, will now cause the stepping relay 205 to retract its armature, opening the circuit for relay 215 which in turn retracts its armature. Relay 216 being slow to release, remains up throughout the series of impulses. With each deenergization of the relay 215, a circuit is completed from the 48 volt battery through the primary stepping magnet 217 and the escape relay 218 in parallel, and 110 thence through the front contact and armature of relay 216 and the back contact and armature of relay 215 to ground. Magnet 217 and relay 218 will both be energized, and relay 218 will close a circuit from battery through the left winding of the escape magnet 214, armature and contact of relay 218, wiper 219 and the right winding of magnet 214 back to battery, thus energizing the escape magnet. The side switch, 115 however, will not be operated this time until the escape magnet is deenergized. Relay 218 being slow to release, is held up during the series of impulses. Magnet 217 rapidly attracts and retracts its armature moving the 120 125 side switch, and the escape magnet is deenergized. Relay 218 being slow to release, is held up during the series of impulses. Magnet 217 rapidly attracts and retracts its armature moving the 130

brushes 209, 210 and 211 of the selector switch from group to group of the trunk terminals.

Upon the termination of the series of impulses, relay 205 will remain energized, and will hold the circuit for relay 215 closed. Relay 218 will then retract its armature, opening the circuit for the escape magnet 214 and causing the side switch to move to position 3. As the side switch moves to position 3 the circuit for relay 215 is interrupted, and it retracts its armature, but a substitute circuit is completed for the holding relay 216 through the side switch wiper 213 in position 3, thus preventing the release of the switch.

The escape magnet 214 is employed as a test relay. In position 3 of the side switch, a circuit is closed from the 24 volt battery through resistance 220, wiper 219 and the right winding of relay 214 to ground. The current flowing over this circuit is, however, insufficient to cause magnet 214 to pull up its armature. At this time, a circuit is closed from battery through the left winding of magnet 214 and wiper 221 to the test brush 209 of the selector switch. The test or guarding contacts of trunks leading to idle selector switches will be connected to ground through a side switch wiper as 13 at the second selector and the left winding of the escape magnet 214 of that switch. If, however, a trunk leading to such switch is busy, its test or guarding contact will be provided with battery potential. This may be supplied in several different manners, depending on the stage of operation of the switch which has selected the connecting circuit, and of the switch at which the circuit terminates. If the connecting circuit has just been selected at one of its multiples and the side switch of this connecting circuit has moved to position 2, it is obvious that the test contacts will be connected to the 48 volt battery through wiper 13 and stepping relay 215'. At this time, however, the 24 volt battery at the impulse relay 205 will also be connected to said test contact by a circuit extending through wipers 213 and 221, in position 4. Therefore, the potential of the test contact will be of substantially 24 volts, and current will therefore not flow through the left winding of magnet 214 in such a manner as to cause its energization. If the impulse wheel connected to the connecting circuit is at this time transmitting impulses, the battery at the impulse relay 205 will be removed from the multiple test contacts of the connecting circuit with each deenergization of relay 205, leaving only the 48 volt battery at relay 215 associated with said contacts. The flow of current, however, from this battery through the left winding of magnet 214, is in a direction to oppose the flow of current through its right winding, and magnet 214

will not be energized. If the side switch wiper of the switch at which the connecting circuit terminates is in position 3 or position 4, the same condition will exist, except that the test contact will be connected to the 48 volt battery through relay 216 instead of through relay 215'. If the switch associated with a multiple of the connecting circuit is just in the process of testing and the side switch has not yet moved to position 4, the second switch to arrive on the multiple test contact will find battery potential thereon and its test relay or magnet 214 will not be energized. When the second selector side switch was moved to position 3, a circuit was established from battery through the secondary stepping magnet 222, wiper 223 and interrupter 224 to ground. This circuit will be maintained and the brushes 209, 210 and 211 will be stepped from trunk to trunk until the contacts of an idle trunk are engaged, when current will flow through the left winding of magnet 214 in a direction to assist the current flowing through its right winding, thus energizing the escape magnet 214 and moving the side switch to position 4.

It is obvious from the preceding description in what manner succeeding selector switches would be operated. The secondary magnet of the connector switch might be arranged to be substituted by a side switch wiper for the primary magnet in the circuit controlled by relay 215. It is believed this is obvious and will not require further description.

By means of the apparatus of Fig. 1 shown and described or otherwise indicated, the talking conductors 111A and 112A of the connecting circuit of Fig. 4 are extended to the calling line having a substation A; this circuit being independent of the circuit previously had which may be called an instruction circuit for the operator from the said line. A conversational circuit is now complete including the said conductors and contacts of the switches of the system of Fig. 5 from the calling subscriber's line to the called subscriber's line, through the talking conductors 111A and 112A of the connecting circuit of Fig. 4A and contacts 62 and 244 of the relay 63 of the said connecting circuit, and through co-operating contacts of the plug and jack switch P1—J3, by means of which as has been described, connection is made with the called line LL shown in Fig. 1. The ringing of the called substation may now proceed in the usual manner for manually operated systems.

The circuit of the impulse conductor 110A—110, of Figs. 4A and 5, is controlled by contacts 508 of the relay 509, and these contacts remaining closed during successive sets of impulses until a series of selector switches of Fig. 5 are operated as described, to make connection with the calling

line. The conversational circuit established through the conductors and contacts of the switches of the system of Fig. 5 of the calling subscriber's line to the plug connecting circuit CP of Fig. 4^A, is now operative to cause the operation of the bridged subscriber's battery feed relay 631, which is now included in circuit with the subscriber's line through the said contacts, the circuit including the subscriber's instrument and the central office source of current. The relay 631 will thereupon attract its armatures upon the flow of current through the said circuit and from the said source contacts 632 and 15 633 being closed. The contacts 623 being closed, a circuit will be completed including the said contacts, a winding 635 of the relay 509 and now closed contacts 478 of the relay 465, together with the source of current. Current from the said source will flow over the said circuit operating the relay 509, which will attract its armatures closing the contacts 636 and 637, and opening the contacts 508, the mechanical arrangement being such that the contacts 637 are closed before the contacts 508 are opened. This in order to maintain the circuit of conductor 110 controlling the selective switch system of Fig. 5 closed, even though the original circuit for the said switches through the contacts 508 are opened, the circuit being maintained closed through the contacts 637 and the winding of a relay 638, to the ground pole of battery. The relay 638 being included in this circuit, current will flow through its winding and out over the conductor 110, and the relay 638 will be operated, and the relay 205 of Fig. 5 will be maintained operated to hold the established connection. The relay 638 being operated will close contact 639 in the circuit of the calling subscriber's signal 640 which will not at this time be operated, because of the open contacts 634 of the relay 45 631, the said contacts being in its circuit. The relay 509 being operated, as described, a holding circuit is established therefor including contacts 636 closed by its operation and now closed contacts 478 of the relay 465, the said holding circuit including a winding 641 of the relay 509.

The selective system of Fig. 5 having established connection with the contacts of the calling line, a circuit is completed for a 55 winding of the cut-off relay of the calling line, including contacts *bb* of the connector switch, circuit conductor *b* of the line circuit leading through a winding 242 of the cut-off relay C of the line circuit, the said 60 circuit including the central office source of current, contacts of the selector switch system of Fig. 5, and the central office source of current. The cut-off relay C will thereupon be operated, opening its contacts 1 and 65 3 in the circuit of the line relay 6 to deen-

ergize the said line relay, and the contacts 2 will be closed to connect the circuit conductors *a* and *b* of the line together, so that the increased potential of the conductor *b* may be duplicated on the conductor *a* in order to make the test contacts *x* and *y* of the multiple jack of the said calling line test busy to prevent the intrusion of another operator's connecting circuit. The line relay 6 of the line being deenergized, it will open its contacts 7, 8 and 9 to restore the relay 12 of the line circuit, and the relays 19 and 21 of Fig. 1, and 27, 32 and 34 of Fig. 3, together with the relays 44, 49, 60, 988 and 514 of Fig. 4; these relays being involved in the connecting system for the instruction circuit which has been described, and in turn successively controlling various portions of the instruction circuit, each of the relays being controlled by preceding relays in the instruction circuit, and the contacts of the controlling line relay 6 being opened, these relays will be all restored to normal as will be apparent from the foregoing description, allowing the instruction circuit connecting links involved in the established instruction circuit connection to revert to the use of a subsequent incoming call.

The ringing of the called substation is initiated by the depressal of one of the keys K₁, K₂, K₃ or K₄ depending upon which station of a party line, if the called line is a party line, it is desired to signal, and the contacts 640 which are mechanically associated with all of the ringing keys will be momentarily closed during the depressal of any of the ringing keys, these ringing keys being mechanically locked in ringing position. The ringing relay 463 is operated and the ringing proceeds. The circuit for the ringing relay 463 includes its winding and the contacts 640, together with normal contacts 641 of the relay 483, and now closed contacts 633 of the relay 631, resistance coil 642 and now closed contacts 479 of the relay 465, together with the central office source of current. Upon the operation of the relay 463, the contacts 643 thereof are closed, bridging the contacts 640 of the ringing key to cause the locking circuit for the relay 463 independent of the said key contacts.

The contacts 644 and 462 of the relay 463 are now opened, opening the talking conductors leading to the plug P1, which is understood to be now inserted into the jack J3, and the contacts 645 and 646, leading from the key selected ringing generator, such as the generator G1, and the serially included central source of current as B₁. Current from the said ringing generator will flow through the said ringing contacts 645 and 646, through the talking conductors 461 and 647, leading to the called plug, and 130

from thence through the contacts of the plug and jack switch P1 and J3, and over the line conductors 248 and 249 of the called line, and through the windings of the called 5 subscriber's telephone bell 250, ringing the said telephone bell. The called subscriber answering his telephone will remove his receiver from the hook, closing contacts 251 bridging his telephone transmitter across 10 the telephone line, and current from the central source of current B_1 flowing over the circuit for direct current thus established, will operate the trip relay 652 in the plug connecting circuit CP of Fig. 4^A, causing it 15 to close its contacts 653 to bridge the said contacts across the winding of the ringing relay 463 to deenergize the said relay and cause it to restore its armatures to normal, opening the ringing contacts 645 and 646 20 and the locking contacts 643, and closing the talking contacts 462 and 644. These last-named contacts being closed, a circuit is complete from the subscriber's substation apparatus through the said contacts, and 25 through windings 480 and 680 of the bridged subscriber's battery feed relay 483, and the central office source of current. Current from the said source operating the said relay will cause the contacts 641 in the circuit of 30 the ringing relay 463 to be opened to prevent the reenergization of the said relay, and the contacts 482 to extinguish the signal lamp 484. The subscribers are now in conversational circuit and will so continue until 35 the end of the conversational period, whereupon they will restore their receivers to their hooks, opening their respective line circuits. The opening of the called subscriber's line circuit and of the calling subscriber's line 40 circuit will be evidenced in the operated plug connecting circuit CP, by the lighting of the respective signal lamps for calling and called subscribers 640 and 484, this being caused by the deenergization of the respective bridged battery feed relay for calling and called subscribers 631 and 483. The operator upon observing the lighting signals 45 will disconnect by removing the plug P1 from the called line jack J3, restoring the 50 cut-off relay 71 of the called line to its normal condition and restoring the relay 465 in the plug connecting circuit to its normal deenergized condition. The relay 465 being restored, circuit controlling contacts 476, 55 477, 478 and 479 thereof, will be opened to release the apparatus of plug connecting circuit CP, the contacts 478 being operative to release the relay 503 which thereupon opens its contacts 504 in the circuit of the conductor 110 leading to the relay 205 shown in Fig. 5, the said relay 205 being thereupon restored to normal. The contacts of the relay 205 being opened, the apparatus of the 60 selective switch system of Fig. 5 which is 65 being held operative by the continued clos-

ure of these contacts, will be restored to normal upon the opening thereof, and the switch involved in the established connection as has been described, will be restored to normal position. 70

Now assuming that the system as before described is in operation, it is apparent during busy times of the day more than one call will be awaiting attention on a given operator's position and it may be that such an 75 operator, as for instance that operator whose telephone set is shown at O in Fig. 4^A and upon whose position, for instance five incoming call circuits such as the incoming 80 call circuits M and X fully shown in Fig. 4 reside, and upon whose position other incoming call circuits such as the incoming call circuits S, V and Z not fully shown, but portions of which are shown in Fig. 4 reside. Such incoming call circuits may 85 contain resident unanswered calls to the number of 2, 3 or more up to 5 unanswered calls, and it is apparent that in the case of a relatively slow operator, that if means are not provided to assist in the speeding up of the 90 answering operation, that confusion will result, or all of the operators will necessarily be required to answer calls at a rate of speed set by the slowest operator. 95

In the system of my invention and by the means now about to be described in detail, I provide assistance for the slower operators, or for such positions in which for some reason or another, more than a predetermined number such as more than two unanswered 100 calls, have become resident in incoming call circuits of the position. A representative operation of the apparatus involved will now be described wherein there are two unanswered incoming calls resident in the call 105 circuits M and X, and thereafter a call comes in on incoming call circuit S in the same manner as for the other call circuits, the result being that for the call circuits M, X and S, call signal controlling relays 44 110 for the circuit M, 544 for the call circuit X, and 545 for the call circuit S will be operated, this being done in the manner previously described for the relays 44 for the call circuit M. The signal lamp 47 of the 115 call circuit M has been lighted as in the manner previously described to indicate the incoming call on the call circuit M, and in like manner the signal lamp 547 indicates the call on the call circuit X, but when the 120 relay 545 in response to the receipt of a call on call circuit S is made to operate, contacts 542 thereof operate to close a circuit closed at another point by now closed contacts 543 of the relay 44 for the relay 537 individual 125 to the call circuit M. This relay 537 may be called the "call transfer" relay for its function is to transfer the call before the operator of the home position whose operator's set is shown at O in Fig. 4^A, to an operator 130

at the over-flow position whose telephone set is shown at OO in Fig. 4^B. The relay 537 is operated over a circuit traced as follows: from the negative pole of battery, 5 through the winding of the relay 537, through the contacts 542 of the relay 545 of call circuit S, through contacts 543 of the relay 44, and through normal contacts 546 of the relay 49 of call circuit M. The relay 10 49 denotes by its unoperated normal, or operated abnormal position, whether or not the listening key 54 of the incoming call circuit has been operated in response to a call resident therein to answer the call.

15 The relay 537 will now be operated and will be operatively locked, the locking circuit therefor being traced from the negative pole from the source of current, through its windings, through its contacts 548, through 20 contacts 543 of relay 44, and through normal contacts 546 of the relay 49, this locking circuit retaining the relay 537 operated subject to the control of the included contacts 543 of the relay 44. The relay 537 being 25 operated, will extinguish the signal lamp 47 due to the breaking of the contacts 536 in its circuit. A signal lamp 549 will instead, be lighted, to denote to the home operator that a call resident in call circuit M has 30 been transferred to the helping or over-flow position. At the helping position to which circuit conductors of the call circuit are extended, as shown in Fig. 4^B, a relay 744 will be operated, the circuit for the said relay 35 being traced from the negative pole of battery, through its winding, over circuit conductor 550 which continued in Fig. 4 leads through the now closed contacts 551 of the locked relay 537, to the ground pole of battery, the winding of the relay 744 being connected in multiple with the signal lamp 549 at the home position. The relay 744 being 40 operated, will attract its armatures and contacts 745 and 746 will be closed, the latter 45 completing a circuit for a call lamp 747 to indicate the unanswered call to the attendant over-flow operator whose telephone set is shown at OO in Fig. 4^B. This operator will answer the call in the manner as has been 50 described for the operator whose set is shown at O in Fig. 4^A, and will extend the call to the called line in a like manner. The signal lamps 747, 757 and 796 will function 55 in the same manner and for the same purpose as the signal lamps 47, 57 and 96 respectively, as has been described.

For the over-flow position a connecting plug circuit CPA is shown in detail corresponding in function to the connecting plug circuit CP of Fig. 4^A, and an additional connecting plug circuit of the many which would be provided at the over-flow operator's position is shown in part only, at CPB. Circuit conductors 111, 112 and 110 of connecting circuit CPA would be extended to

automatic switching apparatus as illustrated in Fig. 5, and would be connected to circuit conductors with like reference numerals shown in Fig. 5.

The operation of the circuits shown in Fig. 4^B are generally like the operation of the like circuits shown in Fig. 4 and Fig. 4^A. Junction circuit relays 788 and 555 correspond to junction circuit relays 88 and 988 of Fig. 4. Relays 556, 557, 558 and 559 75 correspond to junction circuit relays 511, 512, 513 and 514 of Fig. 4. Controlling relays 515 and 516 of the junction circuit T of Fig. 4 and controlling relays 517 and 518 of the junction circuit U of Fig. 4 find their 80 equivalent in the disclosure of Fig. 4^B in controlling relays 560 and 561 for the junction circuit TT, and controlling relays 562 and 563 for the circuit UU.

It is understood that the conductors WW 85 of Figs. 4^A and 4^B both are connected to the conductors WW of Fig. 1, which is thus extended in like manner to like conductors WW of all connecting plug circuits of a group which may comprise all of such connecting circuits of the exchange or a section 90 of the switchboard only. Conductors 111, 112 and 110 of Fig. 4^B are shown extended to a selective switching system having like conductors illustrated in Fig. 5. 95

The operation of the connecting circuit of Fig. 4^A has been described in connection with the selective switch system of Fig. 5, which illustrates a combination of selective switches for extending the circuit of the 100 manually selected connecting circuit to the terminals of the calling line having the calling substation A located thereon.

For convenience it will be assumed that a duplicate system of conductors and 105 switches as shown in Fig. 5, will be used to extend the conductors 111, 112 and 110 of Fig. 4^B to the terminals of the calling line having the substation A located thereon, so that the disclosure of Fig. 5 will not be duplicated, but it will be understood that although but one finder switch conductor and associated apparatus is indicated in the drawing of Fig. 5, that contacts and conductors would be provided for each connecting circuit, such as CP, CPA, CPB, etc., whereby these connecting circuits may be extended through to such switching system as illustrated in Fig. 5 to make connection with calling lines. 115

The operation of the system of Fig. 5 having been described for the connecting circuit CP, it is unnecessary to repeat the description for the system of Fig. 5 when assumed to be connected to the connecting 120 circuit CPA.

After the impulses have been sent through the switching system of Fig. 5 and the calling line located, the operation of the cut-off relay C, shown in Fig. 1, will as has been 130

described, release the trunk circuits and junction circuits employed in the extending of the line conductors to the listening keys 54 and 754 of Figs. 4 and 4^B, and will dissociate the impulse conductor of Figs. 4 and 4^B from the connecting conductor associated with the calling line, as has been described in connection with the disclosures of Figs. 4 and 4^A.

10 Now, referring again to Fig. 4, it will be seen that if a call existed only on the call circuits X, S and V, that the closure of contacts 564 of the relay 544 of call circuit X and of contacts 565 of the relay 566 of call circuit V, will complete a circuit for relay 567 corresponding to the relay 537 of call circuit M, to operate the relay 567 and to cause the transfer of the call existing on call circuit X to the helping position, signal 15 lamp 568 for the call circuit X at the home position indicated such transfer, and calling lamp 569 at the helping position indicated at that position the transfer of the call, and thus the operator at the home position will 20 now be relieved of the call existing on call circuit X which would be speedily answered at the helping position, and would only have the two calls existing on the call circuits S and V to answer, and would proceed to answer the call on the S call circuit. In the same way when calls exist on both of any two alternate call circuits in the order of the placement of calls, such as call circuits 1 and 3, 2 and 4, 3 and 5, 4 and 1, 5 and 2 25 and so on assuming that there are five call circuits provided, the first in order of the two in each case in the order of the placement of the call will be transferred to the helping position. This is accomplished as 30 can be seen from the foregoing description without the use of any marginal adjustments and ensuing uncertainty in operation.

It will be understood that I have only illustrated and described a specific embodiment of my invention of which many modifications and departures may be made without departing from the spirit and scope of my invention.

I do not wish to be limited to the precise 50 types of switching apparatus and of precise means to accomplish the various functions illustrated and described, but what I claim as my invention is defined in the following claims:

55 1. In a telephone system, the combination of a plurality of telephone lines therefor, substations for the said lines, a main station, a plurality of operator's call answering positions at the main station, a plurality of call 60 circuits for extending incoming calls from calling lines to the said call answering positions, a call signal for each of the said call circuits at each of the said positions, and means responsive to extended calls of a given 65 number, more than one, of the said call cir-

cuits to operate the call signal of one of the call circuits located at a given operator's position, and to extinguish the call signal of the said call circuit at another operator's position.

70 2. In a telephone system, the combination of a plurality of telephone lines leading from substations to an exchange, a group of call answering circuits at the exchange terminating at home positions, a call signal for 75 each of the said positions for each of the said call circuits, trunking means to automatically connect calling lines to the said call circuits, and means responsive to the connection of a given number, more than 80 one, of the said calling lines to call circuits of the group, to extinguish a previously operated signal of one of the call circuits to which has been connected a calling line and to operate the call signal of the last named 85 call circuit at the helping operator's position.

90 3. In a telephone system, the combination with a plurality of telephone lines, calling apparatus on the said lines, line extending apparatus at a main station wherein the lines terminate, means to cause the said line extending apparatus under the control of the said line calling apparatus, to extend calling lines to call receiving circuits, terminal apparatus at a plurality of operators' positions for each of the said call receiving circuits, call signals at a first of the said operators' positions to indicate the presence of calls on associated telephone lines, a relay 95 associated with each call receiving circuit controlling its call signal, successive overlapping controlling circuits for each of the said call receiving circuits of the said first operator's position, each of the said circuits 100 containing contacts of two of the said relays, the wiring of an electromagnet and a source of current controlling the said electromagnet, and means under the control of the said electromagnet to retire the signal of the first 110 of the said two relays, and to operate an associated signal at a second of the said plurality of operators' positions to indicate a call on the associated extended call receiving circuit.

115 4. In a telephone system, the combination with a main switchboard and an associate switchboard, of telephone lines therefor, substations for the said lines, line extending circuits to extend calling lines to the main 120 switchboard and to the associate switchboard, a group of signals at each switchboard for each of the said extending circuits, a relay for each signal to first cause the signals at the main switchboard to operate in 125 response to the connection of calling substations with lines, controlling circuits for the said signals, the said controlling circuits including contacts of a first operated relay and of a later operated relay of the group 130

- whereby a first operated signal is grouped with a later operated signal, and non-marginal controlling means included in the said controlling circuits responsive to the operation of both of the said relays to cause the first operated signal of the said group at the main switchboard to be extinguished and an associated signal at the associate switchboard to be operated.
5. In a telephone system, in combination with a main switchboard and an associate switchboard, of telephone lines therefor, substations for the said lines, call extending circuits to extend calling line circuits to the main and associate switchboards, signals at each switchboard for each of the said call extending circuits, means to first operate the signals at the main switchboard in response to calling substations on the lines, controlling means for each of the said signals, interconnecting grouping circuits for the said controlling means whereby a first operated signal is grouped with a later operated signal, a circuit and windings, contacts of a first and last of the said controlling means of a group, a source of current in the said circuit, an electromagnet individual to the first operated signal of the said group at the main switchboard in the said circuit to retire the said signal and to operate an associated signal at the associate switchboard and a signal at the main switchboard for each of the aforesaid main switchboard signals adapted to be operated when its associated main switchboard signal is retired and the associated switchboard signal is operated.
6. In a telephone system, the combination with a main switchboard and an associate switchboard, of telephone lines therefor, substations for the said lines, line extending circuits to extend calling lines to the main switchboard and to the associate switchboard, signals at each switchboard for each of the said extending circuits, relays for each of the said signals to first cause the signals at the main switchboard to operate in response to the connection of calling substations with the lines, controlling circuits for the said signals, the said controlling circuits including contacts of a first operated relay and a later operated relay, whereby a first operated signal is grouped with a later operated signal, non-marginal controlling means included in the said controlling circuit responsive to the operation of both of the said relays to cause the first operated signal of the said group at the main switchboard to be extinguished and an associated lamp at the associate switchboard to be operated, and a signal at the main switchboard associated with each of the aforesaid main switchboard signals adapted to be operated when its associated main switchboard signal is retired and the associated switchboard signal is operated.

7. In a centrally operated telephone system, the combination with a plurality of telephone lines leading from substations to an exchange, of a plurality of operators' positions at the said exchange, a group of operator's instruction circuits for each operator's position, relatively larger group of line interconnecting link circuits for each operator's position, means to extend calling lines to the said instruction circuits of an operator's position, adjustable terminals for each of the said link circuits to connect with calling and called telephone lines, a group of junction circuits common to an operator's position group of instruction circuits and the associated group of link circuits, the said junction circuit being a relatively smaller group than the other groups, and means responsive to the manual operation of an adjustable terminal of one of the said link circuits including connection with the called line to temporarily associate the said link circuit and a previously attended instruction circuit, the said associating means including an automatically selected junction circuit of the associated relatively small group of junction circuits and a line identifying conductor extending to the said link circuit through the temporarily associated call receiving circuit and junction circuit to automatically and directly operate the other adjustable terminal of the said link circuit to make connection with the calling line.

8. In a centrally operated telephone system, the combination with a plurality of telephone lines leading from substations to an exchange, of a plurality of operators' positions at the said exchange, a group of operator's instruction circuits for each operator's position, relatively larger group of line interconnecting link circuits for each operator's position, means to extend calling lines to the said instruction circuits of an operator's position, adjustable terminals for each of the said link circuits to connect with calling and called telephone lines, a group of junction circuits common to an operator's position group of instruction circuits and the associated group of link circuits, the said junction circuits being a relatively smaller group of circuits than the other groups, and means responsive to the manual operation of an adjustable terminal of one of the said link circuits including connection with the called line to temporarily associate the said link circuit and a previously attended instruction circuit, the said associating means including an automatically selected junction circuit of the associated relatively small group of junction circuits and a line identifying conductor extending to the said link circuit through the temporarily associated call receiving circuit and junction circuit to automatically and di-

rectly operate the other adjustable terminal 5 of the said link circuit to make connection with the calling line, and means responsive to the establishment of the connection between the link circuit and the calling line to free the said junction circuit from the said associated link and instruction circuits.

9. In a signaling system, the combination with a set of signal lamps, means to operate each lamp of the set in turn, a plurality of circuits equal in number to the said lamps, each circuit controlling one of the said lamps, and controlling means for each of the said circuits under the joint control of its controlled lamp actuating means, and of a certain subsequently operated lamp actuating means, and means under the control of the said controlling means to cause the associated lamp to be extinguished and a related 20 lamp to be lighted.

10. In a signaling system, in combination, a group of signals, a relay for each of the said signals to operate it, an associated relay for each of the said signals, contacts 25 for the said associated relay to open its associate signal circuit when the said associated relay is operated, relay operating means, sequence means to cause the said relay operating means to operate each of the 30 said first named relays in sequence, a circuit for each of the said associated relays, each of the said circuits containing normally open contacts of its associate signal operating relay and normally open contacts of a later 35 operated signal operating relay, and contacts operated responsive to the closure of the said associated relay circuit to maintain the said associated relay circuit closed independent of the closure or opening of the 40 later operated relay contacts.

11. In a signaling system, in combination, a group of signals, a relay for each of the said signals to operate it, an associate relay for each of the said signals, contacts for the 45 said associated relay to open its associate signal circuit when the said associated relay is operated, relay operating means, sequence means to cause the said relay operating means to operate each of the said first named 50 relays in sequence, a circuit for each of the said associated relays, each of the said circuits containing normally open contacts of its associate signal operating relay and normally open contacts of a later operated 55 signal operating relay, and contacts operated responsive to the closure of the said associated relay circuit to maintain the said associated relay circuit closed independent of the closure or opening of the later operated 60 relay contacts, a second signal, a circuit therefor, the said circuit including a source of current and normally open contacts of the said associated relay.

12. In a telephone system, in combination, 65 a group of telephone lines, substations for

the said lines, a group of signals, a call signal relay for each of the said signals, a controlling relay associated with each of the said call relays, each of the said signals being under the joint control of the said 70 controlling relay and said call signal relay, means responsive to the connection of a calling substation to a telephone line to operate one of the call signal relays, sequence means to cause succeeding connections to operate 75 the other call signal relay in sequence, a circuit for each of the said controlling relays, each of the said circuits containing a pair of sets of contacts, one of the said sets being controlled by a call signal relay, and another of the said sets being controlled by a later operated call signal relay, the said associated relay being operated when both sets of contacts are closed.

13. In a telephone system, in combination, 85 a group of telephone lines, substations for the said lines, a group of signals, a call signal relay for each of the said signals, a controlling relay associated with each of the said call relays, each of the said signals being 90 under the joint control of the said controlling relay and said call signal relay, means responsive to the connection of a calling substation to a telephone line to operate one of the call signal relays, sequence means to 95 cause succeeding connections to operate the other call signal relays, each of the said circuits containing a pair of sets of contacts, one of the said sets being controlled by a call signal relay, and another of the said 100 sets being controlled by a later operated call signal relay, the said associated relay being operated when both sets of contacts are closed, and an extension signal for each of the said first named signals, said extension signal being under the control of the 105 said associated relay.

14. In a telephone system, the combination of a telephone switchboard divided into normal answering and abnormal helping sections, of a plurality of telephone lines, extension circuits for the said telephone lines, each of the said extension circuits terminating at each of the switchboards in call answering connection switches, of signal lamps 110 for each of the said extension circuits associated with the said call answering switches, and common controlling means to selectively operate the signal lamps of an extension circuit, the said selection being under the 115 joint control of non-marginal apparatus in a plurality of call responsive apparatus in different extension circuits.

15. In a telephone system, the combination with an operator's instruction circuit for 125 calling telephone lines, of a signaling circuit for the said instruction circuit, the said signaling circuit being under the control of subscribers' line apparatus, of a plurality of operators' link circuits, call attending means 130

for the said instruction circuit, a manually operated connection switch for each of the said link circuits, an automatic adjustable connection switch at the other end of each 5 of the said link circuits, an inter-instruction circuit link circuit junction system responsive to the operation of the said manual connection switch to inter-link the associated link circuit with one of the instruction circuits having a non-completed call resident 10 therein, each of the said junctions being common to a plurality of link and instruction circuits.

16. In a telephone system, a plurality of 15 telephone lines, a plurality of call receiving circuits therefor, means to cause calling lines to be connected to idle call receiving circuits, a call answering operator's position, an alternating call operator's position at which 20 the said call receiving circuits terminate, a call lamp at each of the said positions for each of the said call receiving circuits, and selective call signal operating means under the control of switch contacts associated 25 with a plurality of call receiving circuits.

17. In a telephone system, a plurality of telephone lines, a plurality of call receiving

circuits therefor, means to cause calling lines to be connected to idle call receiving circuits, a call answering operator's position, an alternating call operator's position at which 30 the said call receiving circuits terminate, a call lamp at each of the said positions for each of the said call receiving circuits, selective call signal operating means under the control of switch contacts associated with a plurality of call receiving circuits, a line inter-connecting link at each of the said positions adapted to be manually associated with a last attended one of the said call receiving circuits, and to be automatically dissociated therefrom when connection is made between calling and called telephone lines. 35

18. The method of handling telephone calls which consists of distributing calls to 40 operators in succession, in transferring calls to helping operators when any of said first named operators become over busy, manually extending a connection to the wanted line and completing the partially extended connection automatically to the calling line. 45

In witness whereof, I hereunto subscribe my name this 29th day of June, A. D. 1918.

FRANK M. SLOUGH.
